UNITED STATES PATENT OFFICE.

GEORGE T. BROWN, OF FREELAND, PENNSYLVANIA, ASSIGNOR TO THOMAS BROWN, OF SAME PLACE.

CYCLOMETER.

SPECIFICATION forming part of Letters Patent No. 634,610, dated October 10, 1899.

Application filed January 24, 1898. Serial No. 667,757. (No model.)

To all whom it may concern:

Be it known that I, GEORGE T. BROWN, a citizen of the United States, residing at Free-
land, in the county of Luzerne and State of
Pennsylvania, have invented a new and use-
ful Cyclometer, of which the following is a
specification.

My invention relates to a cyclometer at-
tachment for vehicles, and particularly for
conveyances, such as carriages and wagons;
and the object in view is to provide means
for applying a cyclometer to a vehicle in such
a position as to be protected from contact
with contiguous objects and to receive mo-
tion from the rotation of the wheel without
necessitating the provision of standards or
similar devices for supporting the cyclometer
to arrange its operating or star wheel in a
position to be engaged by the wheel-spokes,
and particularly to provide a cyclometer at-
tachment of such a construction as to be un-
affected by the backward rotation of the
wheel, whereby the registration of forward
rotations may not be altered by the subse-
quent backward rotation of the wheel by
which the cyclometer is operated.

A device of the class to which my invention
belongs is particularly applicable to vehicles
supplied by livery-stables, &c., and hence
should be so constructed as to accurately
register the distance traveled by a hired ve-
hicle and at the same time prevent custom-
ers from "fixing" the register or turning the
same back to mislead the dealer, and in order
to accomplish this I have adopted a clutch
connection between the operating or star
wheel and the cyclometer-spindle whereby
only during the forward rotation of the wheel
of the vehicle is motion communicated to the
registering or tally mechanism.

Further objects and advantages of this in-
vention will appear in the following descrip-
tion, and the novel features thereof will be
particularly pointed out in the appended
claims.

In the drawings, Figure 1 is a perspective
view of a cyclometer attachment constructed
in accordance with my invention applied in
the operative position to a vehicle-wheel.
Fig. 2 is a longitudinal section of the same.
Fig. 3 is a detail view in perspective of the nut

and the seat for the cyclometer-casing. Fig. 4
is a detail transverse section in the plane of
one of the clutch members on line 4 4 of Fig.
2 to show the means for preventing backward
rotation of the cyclometer-spindle. Figs. 5,
6, 7, and 8 are detail views, respectively, of
the cyclometer and operating clutch mem-
bers, the tension-adjusting nut, and the star-
wheel-operating stud detached. Fig. 9 is a
detail view of the star-wheel. Fig. 10 is a
view of a portion of the nut and cyclometer-
seat, showing the method of permanently se-
curing the cyclometer-casing in engagement
therewith. Fig. 11 is a side view of the same. 65

Similar numerals of reference indicate cor-
responding parts in all the figures of the draw-
ings.

1 designates a vehicle-wheel nut which in
essential features is identical with those now 70
in common use, but which at its outer flat
surface is constructed to form a seat for a
cyclometer-casing 2, (the construction of the
interior mechanism of the cyclometer form-
ing no part of my invention, and hence not 75
being illustrated in detail in the drawings.)
Said cyclometer-casing seat is of cross-section-
ally-dovetailed shape, and consists of parallel
oppositely-disposed flat ribs 3, which are un-
dercut at their inner edges to receive the bev-
eled edges 4 of the base 5, with which the cy-
clometer-casing is provided. A fixed stop 6
is arranged between the strips or guides 3 in
the path of the cyclometer-base to prevent
displacement in one direction, and the oppo- 85
site ends of the guides or strips are spaced
from the surface of the nut sufficiently to re-
ceive the reduced extremities of a securing-
bar 7, which may be held in place by means
of securing devices, such as screws 8, to lock 90
the cyclometer-base from displacement in the
opposite direction. In the construction illus-
trated in Fig. 10 the securing-bar 7 is omitted,
and said spaced extremities of the guides or
strips 3 are bent or deflected downwardly to 95
close the undercut ways or grooves in the in-
ner edges of the strips after the cyclometer-
base has been inserted. This forms a per-
manent means of securing the cyclometer-
base in its seat. 100

9 represents a cyclometer-spindle extended
to form a clutch member 10, of which the face

is adapted to interlock with the corresponding face of an operating clutch member 11, mounted for rotary and reciprocal movement in a guide-tube 12. This guide-tube, which 5 is slightly enlarged contiguous to the plane of the head of the cyclometer-easing, is threaded upon a boss or shoulder 13 on said casing, and carried by the guide-tube, contiguous to the plane of the casing-head, is a stop or 10 check-pawl 14 for engagement with radial projections or teeth 15 on the periphery of the clutch member 10 to prevent backward rotation of said clutch member, and hence of the cyclometer-spindle, while permitting free forward rotation thereof to actuate the registering mechanism of the device.

Threaded in the outer or remote extremity of the guide 12 is a nut 16, adapted to perform the function of an adjusting device for 20 the actuating-spring 17 of the operating clutch member 11, said spring being coiled upon the stem 18 of said operating clutch member and bearing terminally, respectively, against the outer side of the clutch member 25 11 and the inner side of the adjusting-nut 16. Said spindle also carries an operating or star wheel 19, of which the radial slightly-curved arms are arranged in the path of an operating pin or stud 20, secured to the hub 21 of 30 the wheel with which the cyclometer attachment co-operates and projecting inwardly from the wall of said hub by which the cyclometer attachment is encircled. This operating pin or stud is preferably provided with a shoulder 35 22 to bear against the inner surface of the wall of the hub and a stem 23 to extend through a radial perforation of said wall and adapted to be swaged on the outer surface thereof.

40 The operating pin or stud 20 projects inwardly from the wall of the hub and comes in contact at each revolution of the wheel-hub with one of the forwardly-concaved arms of the star-wheel 19, thus imparting a partial 45 rotary movement to said star-wheel, and thus through the spindle 18 and interlocked clutch members 10 and 11 to the spindle of the cyclometer, whereas the rotation of the wheel-hub in the opposite direction, while actuating 50 the star-wheel as above described, simply causes the reciprocable clutch member 11 to slide loosely over the cyclometer clutch member 10 without communicating rotary motion thereto.

55 Also from the above description it will be obvious that inasmuch as the entire cyclometer mechanism, with its co-operating parts, (with the exception of the operating pin or stud 20,) is carried by the axle-nut 1 it is 60 adapted to be removed therewith when the vehicle-wheel is to be displaced, but is not only firmly and efficiently retained in place when the nut is in its operative position, but by reason of the nut being arranged in a cap 65 or flange at the outer end of the hub is inclosed and protected by the hub, and hence

is held out of contact with passing objects or with stationary objects passed by the vehicle.

A further advantage of the construction described is that it may be manufactured at a small cost and applied to a vehicle without changing the construction of the latter, except in so far as the attachment of the operating pin or stud 20 is concerned, a nut such as that described having the cyclometer-easing seat being simply substituted for the ordinary nut with which the vehicle is provided. In practice I prefer to employ the cyclometer known as the "Veeder," from the fact that it is of small and compact construction, and while some modification as to the number of teeth with which the registering-disks are provided may be necessary in order to suit the larger diameter of vehicle-wheels over those usually employed on bicycles I have found the above-named cyclometer to be efficient for the purpose described. It will be understood, however, that I do not limit myself to the use of any particular construction of cyclometer, as this is a feature which may be varied without affecting the essential features of the construction specifically described, and it will be understood, moreover, that various other changes in the form, proportion, and the minor details of construction may be resorted to without departing from the spirit or sacrificing any of the advantages of this invention.

Having described my invention, what I claim is—

1. The combination with a cyclometer, and means for mounting the same upon a vehicle-wheel nut, of cyclometer-operating devices including a pin or stud carried by the hub of a vehicle-wheel, substantially as specified.

2. The combination with a cyclometer, of a vehicle-wheel nut having a seat in which the cyclometer-easing is fitted, and operating devices including a pin carried by the vehicle-wheel hub, substantially as specified.

3. The combination with a cyclometer, and means for seating the same upon a vehicle-wheel nut, of operating devices including a star-wheel, and a clutch connection between the star-wheel and the spindle of the cyclometer, substantially as specified.

4. The combination with a cyclometer, and means for securing the same to a vehicle-wheel nut, of operating devices including a star-wheel, a clutch having members connected respectively with the cyclometer-spindle and the spindle of the star-wheel, and means for preventing backward rotation of the cyclometer-spindle, substantially as specified.

5. The combination with a cyclometer-easing, having a cross-sectionally-dovetailed base, of an axle-nut provided at its outer side with a transverse cross-sectionally-dovetailed seat for the reception of the base of the cyclometer-easing, and means for locking said base against sliding movement in the seat, substantially as specified.

6. The combination with a cyclometer, of

an axle-nut provided at its outer side with a cross-sectionally-dovetailed seat having undercut parallel ribs for engagement with the side edges of the base of the cyclometer-casing, a stop located between said ribs to limit movement of the cyclometer-base in one direction, and a locking-strip removably secured between the opposite ends of said ribs, for securing the cyclometer-base against movement in the opposite direction, substantially as specified.

7. The combination with a vehicle-wheel hub, and an axle-nut encircled by the band

at the outer end of said hub, of a cyclometer having its casing seated upon said axle-nut 15 and provided with an operating-wheel, and a shouldered operating-pin engaged with a perforation in the band of the vehicle-hub, substantially as specified.

In testimony that I claim the foregoing as 20 my own I have hereto affixed my signature in the presence of two witnesses.

GEORGE T. BROWN.
